LAUNDRY DRIER

James R. Moore, Two Rivers, Wis., assignor to
 Hamilton Manufacturing Company, Two
 Rivers, Wis., a corporation of Wisconsin

Application September 19, 1945, Serial No. 617,313

4 Claims. (Cl. 34—133)

1

The invention relates generally to apparatus for drying materials and more particularly to an apparatus for drying laundry and adapted for household use.

The general object of the invention is to provide a novel drier adapted to receive laundry after a portion of the water used in washing or rinsing has been removed, as by wringing, and to dry such laundry either to the proper condition for ironing or to a substantially bone dry condition in a relatively short period of time and at a relatively small operating cost.

Another important object is to provide a novel laundry drier which is easy to operate, which is of convenient size so that it may be used with other standard household laundry equipment, and which has a capacity sufficient to accommodate a batch of laundry such as would be washed at one time in a standard washing machine of the household type.

A further object is to provide a laundry drier having a heated chamber in which the laundry is dried and through which a small current of air is caused to flow, the drier having novel means for producing and controlling such current.

It is also an object to provide a laundry drier having a heated chamber in which the laundry is dried, and novel means for producing a current of air to carry away moisture laden air resulting from evaporation of moisture in the laundry, the intake and outlet openings for such air current being provided at the front of the drier so that there will be no interference with the air flow, should the machine be placed adjacent a wall or close to some other equipment or furniture.

Still another object is to provide a novel laundry drier comprising a heated drying chamber, and means for producing an air current for removing moisture from the chamber as it evaporates from the laundry, the air drawn into the drier by said means being at least partially heated, prior to removing such moisture, by heat normally dissipated from said chamber.

A still further object is to provide a novel laundry drier comprising an outer casing and an inner casing providing a drying chamber which is heated, and means for producing a current of air for removing moisture from the chamber as it evaporates from the laundry, at least part of the air drawn into the drier by said means passing through the space between the two casings, prior to removing the moisture, to absorb heat dissipated from said chamber into said space and thereby maintain the outer casing in a relatively

2

cool condition and at the same time increase the moisture absorbing capacity of the air by so heating it.

Another object is to provide a laundry drier comprising a chamber in which the laundry is dried, and an electrical heating element within the chamber for imparting heat to the laundry, the heating element being provided with novel means for causing the various portions of the heating element to operate at substantially uniform temperatures and thereby compensate for the effect on the heating element of air circulation within the chamber.

A further object is to provide a laundry drier comprising a heated chamber in which the laundry is dried, means for producing a current of air for removing moisture from the chamber as it is evaporated from the laundry, and novel means for collecting lint discharged from the chamber, said lint collecting means being readily removable for cleaning and effectively collecting the lint to prevent its discharge into the room in which the drier is located.

Still another object is to provide a novel laundry drier comprising a heated chamber in which the laundry is dried, means for producing a current of air for removing moisture from the chamber and having an outlet adjacent the floor, and means provided in the outlet arranged to prevent the air from impinging directly against the floor and any adjacent external portion of the drier, to eliminate condensation of the moisture carried by the air current as it leaves the drier.

Another object is to provide a novel method of drying laundry as well as a novel method of controlling the operation of an electrical heating element of a laundry drier of the foregoing character.

Other objects and advantages will become apparent from the following description taken in connection with the accompanying drawings, in which:

Figure 1 is a perspective view of a drier embodying the features of the invention.

Fig. 2 is a vertical sectional view taken on a plane extending from the front to the rear of the machine.

Fig. 3 is a horizontal sectional view of the lower part of the machine and taken on the line 3—3 of Fig. 6.

Fig. 4 is a fragmentary vertical sectional view taken on the line 4—4 of Fig. 3.

Fig. 5 is a view of the under side of the heating element.

Fig. 6 is a vertical sectional view taken on the line 6—6 of Fig. 2.

Fig. 7 is a vertical sectional view similar to Fig. 2 but showing a modified form of the machine.

As mentioned above, a drier embodying the features of the invention is adapted to receive laundry after the water has been partially removed therefrom as by wringing and to dry such laundry either to a substantially bone dry condition or to a condition where a small portion of the moisture is left in an evenly distributed condition in the laundry so that it is suitable for ironing. Generally, the drier comprises an outer casing 10 with an inner casing 11 providing a chamber therein in which the laundry is dried. Heat is applied to the drying chamber to facilitate the drying action by increasing the moisture absorbing capacity of the air within the chamber. In order to effect uniform drying of the laundry by exposing all parts of laundry to the heat, the laundry is agitated during the course of the drying by being tumbled in a rotatably driven drum 12 mounted within the chamber.

The moisture in the laundry is evaporated into the air within the chamber, and such air when it reaches the point of being substantially saturated is removed from the chamber and relatively dry air is inducted therein. The machine is so constructed that the flow of air into and out of the chamber is substantially constant throughout the drying operation. By causing the air removed from the drying chamber to reach a condition of substantial saturation before being removed, a minimum amount of heat is lost, since no heated air which has not served its maximum drying function is discharged from the chamber. Thus, the heat supplied to the chamber is held therein to a maximum extent to effect drying, and consequently the cost of operation is maintained at a minimum.

While, in the foregoing, air is stated to be the medium for receiving and carrying the vapor resulting from the drying, it is to be understood that the invention is not limited to air but may utilize any suitable gas as the moisture carrying medium, such as the gases resulting from the combustion of ordinary cooking or heating gas. The term "air" is therefore used, both in the specification and claims, in the foregoing broader sense to include any suitable gas.

The moisture laden air is adapted to be removed from the drying chamber by means which holds the discharge of air to the desired small amount. At the same time, the means for removing the moisture laden air mixes such air with relatively dry air outside the drying chamber but within the machine so that when the total quantity of air is discharged from the machine to the outside atmosphere, it will not be so heavily laden with moisture as to cause undesirable humidity conditions in the vicinity of the machine.

The present invention relates chiefly to the control of the air flow in the machine to effectively attain the above described results. It also relates to the control of air flow within the drying chamber to cause the heating element, which in this instance is electrical, to operate throughout its entire area at a substantially uniform temperature. The present invention also relates to the removal of lint from the air discharged from the machine as well as to so directing the air discharged as to prevent it from impinging on adjacent surfaces which are relatively cool and thus would tend to cause undesirable condensation of moisture from the discharged air.

As shown in Figs. 1 and 2 of the drawings, the outer casing 10 is generally rectilinear in form and is provided with a flat top 13. The front of the casing 10 is provided with a door 14 giving access to an opening 15 through which the laundry may be inserted into and removed from the drum 12. The outer casing 10 at the lower portion of its front is inset as at 16 to provide a toe space permitting the user to stand relatively close to the machine when inserting laundry therein or removing it therefrom.

The inner casing 11, which is spaced from the outer casing 10, is generally cylindrical in form with its axis horizontal and extending from front to rear of the machine. The cylindrical form of the inner casing is varied slightly at its upper left-hand portion, as shown in Fig. 6, to provide a bulge 17 to allow space for an electrical heating unit, indicated generally at 20, between the periphery of the drum 12 and the inner casing 11. The peripheral wall of the inner casing 11 is preferably provided with insulation 18 while the front and rear walls may be provided with insulation 19.

The drum 12 is provided at its front with an opening 21 concentric with the opening 15, the flanges providing the openings overlapping as shown in Fig. 2, so that clothes may be inserted into the drum without becoming entangled during the tumbling action between the drum and the stationary front wall of the inner casing 11. The drum 12 is supported by a spider 22 secured to the rear face of the drum and having a shaft 23 mounted in a bearing structure indicated generally at 24 and supported by the inner casing 11. The shaft 23 extends rearwardly beyond the bearing structure 24 and has mounted thereon a pulley 25 adapted to be driven by a motor 26 through a suitable drive structure indicated generally at 27. The drive structure 27 is located in the space between the rear wall of the inner casing 11 and the rear wall of the outer casing 10, while the motor in the present instance is located in the lower right rear portion of the machine. The drum 12 is provided with a plurality of inwardly directed vanes or blades 28 for effecting agitation of the laundry during the course of drying.

As mentioned above, the moisture is removed from the laundry by evaporation occurring within the drying chamber, and the vapor resulting from such action is carried out of the drying chamber by means of a flow of air through the chamber. The air which absorbs the moisture is such that when it leaves the drying chamber, it is in a substantially saturated state. To produce such a flow of air into and out of the chamber, a relatively large current of air is caused to flow across an opening in the inner chamber to withdraw moisture laden air therefrom by an aspirating action. Such current of air which produces the aspirating action is herein termed a carrier current and preferably is caused to flow through an air passage provided in the lower part of the machine below the inner casing 11. In the present instance, the air passage is provided in a base structure which is arranged to support the inner casing 11 and is carried by a bottom 30 adapted to rest on the floor and which likewise supports the outer casing 10. The opening from the drying chamber, indicated at 31, is preferably located at the bottom of the chamber and extends throughout the length thereof so that not only will air from all portions of the chamber be removed but also any lint re-

sulting from the tumbling of the laundry will likewise be discharged.

The air passage in the present construction comprises an intake portion indicated at 32 which underlies the opening 31 and has a horizontal area substantially equal thereto. The intake portion 32 of the air passage is provided with an opening at one end through which outside air may enter. The base structure is also provided with an outlet portion 33 extending parallel to the intake portion 32 at the right side thereof. Connecting the two portions is a transverse intermediate portion 34 defined by walls substantially parallel throughout their length which opens from the right side of the intake portion 32 and extends in the rear of the outlet portion 33. In order to produce a current of air passing through such portions, the shaft of the motor 26 extends forwardly into a round opening 35 at the rear end of the outlet portion 33 and is there provided with a fan 36 for forcing the air forwardly through the outlet portion. Thus, air will be drawn in through the intake portion below the opening 31 in the chamber and will pass therefrom through the intermediate portion 34 to be discharged from the machine through the outlet portion 33.

From the foregoing, it will be apparent that the carrier current of air passes under the chamber opening 31. By such action, moisture laden air from the chamber is drawn downwardly through the opening 31 by the aspirating action of the carrier current, and such moisture laden air mixes with the carrier current before being discharged from the machine. Since it may often be desirable to place the machine with its rear or one of its sides against a wall or close to other equipment or furniture where any air openings would be obstructed to some extent, both the intake portion 32 and the outlet portion 33 are open at their front ends as indicated at 37 and 38.

The rear wall of the intermediate portion 34 is provided with an opening 40 through which the motor shaft extends, and some air is admitted through such opening 40 but such air is insufficient, in view of the capacity of the fan, to decrease the flow in the intake portion 32.

As shown by arrows in Fig. 3 of the drawings, the carrier current of air enters the intake portion 32 through the front opening 37 and flows inwardly and around the entire portion thereof and thence into the intermediate portion 34. Such action draws moisture laden air as well as lint downwardly through the opening 31 in the chamber to be carried away with the carrier current. The carrier current moves laterally through the intermediate portion 34 to the fan 36 where it is forced forwardly through the outlet portion 33 to be discharged through the front opening 38 thereof.

Since some lint from the laundry will result from the tumbling and drying action in the chamber, it is, of course, desirable to carry away and discharge such lint from the chamber as it is formed rather than permit it to collect therein. Since the opening 31 from the chamber extends the full length of the inner casing 11, the lint forming within the chamber will be completely discharged through the opening 31. It is also obviously desirable to prevent such lint from being discharged into the atmosphere of the room in which the machine is located. To prevent such occurrence, a lint catcher is provided in the outlet portion 33 of the air passage. The lint

catcher in the present instance comprises screening 41 bent into the form of a V to provide two surfaces through which the air may pass in being discharged from the machine. Thus, as the openings of the screening 41 become covered with lint, there will still be an adequate outlet area therethrough for the passage of the current of air without offering any substantial resistance thereto. The lint catcher in its preferred form is constructed as a removable unit and to this end, the screening 41 is secured at its sides to vertically extending plates 42. The lint catcher is mounted in the outlet portion 33 and is removable through the front opening 38 thereof merely by sliding it forwardly. Thus, the lint catcher is dimensioned so that it has a width substantially equal to the width of the outlet portion 33 and the two arms of the V are mounted so that their ends are positioned in the opening 38 and extend inwardly therefrom as is clearly apparent from an inspection of Figs. 2 and 4, the spread of the V being substantially equal to the height of the outlet opening 38.

Since the air current emerging from the front opening 38 of the outlet portion carries more moisture than the outside atmosphere and is at a higher temperature than the outside atmosphere, due to the air removed from the drying chamber, there would be a tendency for some of the moisture to condense on the floor in front of the machine or on the adjacent inset portion 16 of the outer casing, if the outflowing air were permitted to impinge thereon. To prevent such occurrence, air deflecting lips 43 are provided on the lint catcher at its forward end to prevent the outflowing air from diverging downwardly toward the floor or upwardly toward the inset portion 16 of the outer casing. Thus, the lips 43 direct the air in a horizontal direction outwardly from the opening 38 to mix with the outside atmosphere before any substantial quantity of moisture can be condensed therefrom. Preferably, the lips 43 are formed as reinforcements for the front edges of the screening 41.

Another feature of the invention resides in the control of the air circulation within the drying chamber so that the various portions of the heating element 20 will operate at a substantially uniform temperature. In the operation of the drier, the drum 12 is rotated in a counterclockwise direction as viewed in Fig. 6, and as a result of such rotation, the laundry is carried upwardly on the right side of the drying chamber by the blades or vanes 28. As the laundry approaches the top, it slides or is pitched off the blade 28 and tends to spread out as it falls to the bottom of the chamber. Such spreading of the laundry tends to expose all parts thereof to the radiant heat from the heating element 20, and at the same time forces air downwardly in the chamber. Some of this air will flow downwardly through the opening 31, as indicated by the arrows 44, to be discharged from the machine by means of the carrier current. However, some of this air will be diverted to move upwardly in the drying chamber, as indicated by the arrows 45. This portion of the air will strike the lower heat coils 46 of the heating element 20 and tend to cause them to operate at a somewhat lower temperature than the upper coils.

To compensate for this tendency, the upper heat coils of the element are adapted to be correspondingly cooled. To this end, the reflector,

indicated at 47 (see Figs. 5 and 6), of the heating element 20 is provided with a row of small holes 48 adjacent the upper coils, to supply a light current of relatively cool air directed toward the upper coils. Such air is supplied through a number of small apertures 49 in the rear wall of the inner casing 11.

Thus, the upper coils of the heating element are cooled substantially the same extent as the lower coils 46, by the air entering through the apertures 49 and the holes 48. The quantity of air thus introduced is small compared to the air flowing into and out of the opening 31 to carry away moisture. Moreover, such air is heated by its passage through the heating element and thus serves as an effective means for absorbing moisture evaporated from the laundry. Furthermore, such flow of air, by passing through the space between the reflector 47 and the adjacent peripheral wall of the inner casing 11, absorbs some of the heat emanating from the back of the reflector toward the casing wall and thus prevents loss of heat through the wall of the casing.

In the operation of the drier, assuming that the heating element 20 is operating and the motor 26 running, the laundry to be dried is placed in the drum 12 through the opening 15, and the door 14 is then closed. The drum 12 is rotated by the motor 26 so that the laundry is constantly tumbled while heat is applied thereto from the heating element 20, and a drying action or evaporation of the moisture in the laundry thus takes place. The vanes 28 provided on the inside of the drum 12 lift or carry the laundry upwardly at one side of the machine and as it approaches the top thereof, the weight of the laundry is sufficient to cause it to fall downwardly more or less diametrically across the drum. This tends to open out the laundry and subject all parts thereof to the heat within the chamber and particularly to the radiant heat from the heating element 20 since the laundry tends to spread out in a plane generally transverse to heat rays emanating from the heating element 20. Thus, moisture is removed from the laundry and the air within the chamber becomes laden with moisture, the moisture absorbing capacity of the air being substantially increased by the heat within the chamber. Due to the air flow induced by the carrier current in the lower part of the machine, moisture laden air is withdrawn through the opening 31 in the bottom of the chamber, chiefly through the part thereof adjacent the intermediate portion 34 of the air passage. Removal of such moisture laden air necessarily will induce a flow of air into the chamber and such inflow will occur through any opening provided in the chamber. In the present instance relatively dry air taken from the carrier current flowing through the intake portion 32 enters the drying chamber through the opening 31 to replace the moisture laden air theretofore removed. Thus, a constant flow of air into and out of the drying chamber is induced by the carrier current which likewise serves to carry away the moisture laden air and discharge it entirely from the machine.

In the modified form of machine shown in Fig. 7, the carrier current of air is heated to a certain extent prior to passing under the opening 31 so that its moisture absorbing capacity is increased and the air entering the drying chamber is at a somewhat higher temperature. This tends to conserve the heat within the drying

chamber imparted to the contents thereof by the heating element 20.

To the foregoing end, the intake portion 32 of the air passage in the lower part of the machine has an opening 50 connecting it with the space between the inner casing 11 and the outer casing 10, and heat dissipated from the inner casing 11 to such space is utilized to effect pre-heating of the air drawn into the intake portion 32. To provide for such flow of air through the space between the inner and outer casings, the top 13 is provided with an opening remote from the opening 50. In the present instance, such opening comprises a plurality of slots 51 formed at the upper rear edge of the outer casing 10 so that air will flow through the space between the two casings immediately under the flat top 13, thence downwardly at the front of the machine, and thence into the intake portion 32 through the opening 50. Heat which would otherwise be lost through dissipation from the inner casing 11 is thereby utilized to preheat the air drawn into the intake portion 32 to further its drying action. Moreover, such flow of air immediately within the outer casing 10 tends to maintain the outer casing cool, where it otherwise would be heated to some extent by the dissipated heat, particularly the front and top of the outer casing which an operator is apt to contact in using the machine. Furthermore, by preheating the air entering the intake portion 32, any tendency toward condensation of the moisture from the drying chamber when it passes through the intake portion 32 will be prevented.

While the bulk of the air supplied to the intake portion 32 of the air passage is drawn from the space between the inner and outer casings, an opening 52 may also be provided at the front of the intake portion below the inset 16 of the outer casing to permit entrance of air directly from the outside atmosphere. Other than as above described, the machine shown in Fig. 7 operates in the same manner and is constructed in substantially the same way as the machine shown in Figs. 1 to 6.

I claim:

1. A laundry drier comprising a cylindrical casing mounted on a horizontal axis and having an opening in its bottom, a rotatably driven drum mounted within the casing for receiving the laundry to be dried, means for supplying heat to the interior of said casing, a base having an air passage therein comprising an intake portion extending parallel to the axis of the casing and having a length at least equal to and underlying said opening to communicate therewith throughout the length of the opening, said intake portion being open at one end to the outside atmosphere, an outlet portion open at one end to the outside atmosphere, and a portion extending transverse to said intake portion and defined by walls substantially parallel throughout their length and communicating with said intake portion only in the central part of one side thereof and with said outlet portion, and means for drawing air entering the open end of said intake portion through the latter and the transverse portion and discharging it through the open end of said outlet portion.

2. A laundry drier comprising an outer generally rectilinear casing having a flat top, an inner cylindrical casing within and spaced from said outer casing, said inner cylindrical casing having an opening in the lower portion thereof, a rotatably driven drum mounted in said inner

casing, means for supplying heat to the interior of said inner casing, a base supporting said casings and having an air passage open at an intermediate point and communicating with the interior of said inner casing through said opening, said passage having an outlet opening to the outside atmosphere at one end of the passage and an intake communicating with the space between the casings at the front of the casings, said intake being disposed at the end of the passage opposite the outlet, and means for creating an air current through said passage and past the opening in the inner casing to draw moisture-laden air from the interior of said inner casing, said outer casing being provided with an opening providing communication from the outside atmosphere to said space adjacent the upper rear edge of said outer casing whereby air will flow through the space under said flat top to absorb heat dissipated from said inner casing and thereby maintain said top cool, the absorbed heat preventing condensation of moisture from the moisture laden air when it contacts said air current.

3. A laundry drier comprising an outer generally rectilinear casing having a flat top, an inner cylindrical casing within and spaced from said outer casing, a rotatably driven drum mounted in said inner casing, means for supplying heat to the interior of said inner casing, a base supporting said casings with the lower front edge of the outer casing spaced above the lower front edge of the base, said base having an air passage therein communicating with the interior of said inner casing, said air passage having an outlet to the outside atmosphere and an intake open to the outside atmosphere below the lower front edge of the outer casing and to the space between said casings adjacent said lower front edge of the outer casing, and suction means positioned in said outlet for creating an air current through said passage drawn partly directly from the outside into said intake and partly from said space, said outer casing at its upper rear edge having a plurality of openings to admit air to said space from the outside whereby such air will absorb heat dissipated from said inner casing and thereby maintain said flat top cool.

4. A laundry drier comprising a cylindrical casing positioned with its axis horizontal and having a bottom opening, a curved reflector mounted in said casing adjacent the periphery thereof and at one side of the top thereof and providing an arcuate space generally concentric

with said casing and extending downwardly, an electrical heating element mounted in said space and comprising a plurality of coils extending lengthwise of the casing, and a rotatably driven drum mounted in said casing having ribs for agitating the laundry during drying and adapted to carry the laundry up the side of the casing opposite to the side on which said reflector is mounted and to permit the laundry to fall when it reaches a point near the top, the falling of the laundry carrying air downwardly and thereby causing a current of air to move upwardly on the side adjacent the reflector tending to reduce the temperature of the lower coils of said element, said casing being apertured adjacent said reflector to admit air to said arcuate space from outside of said casing to cool said reflector and said reflector being provided with a row of holes only in its uppermost portion adapted to admit air from said arcuate space onto the upper coils to reduce their temperature to substantially the same extent as the temperature of the lower coils is reduced.
